CLAIM

The ornamental design for a vehicle exterior, as shown and described.

DESCRIPTION

FIG. 1 is a front corner perspective view of a vehicle exterior showing the claimed design;

FIG. 2 is a front view of the vehicle exterior;

FIG. 3 is a left-side view of the vehicle exterior;

FIG. 4 is a right-side view of the vehicle exterior;

FIG. 5 is a top view of the vehicle exterior;

FIG. 6 is a rear view of the vehicle exterior; and,

FIG. 7 is a rear corner perspective view of the vehicle exterior.

The broken lines and faded sections within the broken lines represent portions of the vehicle exterior that form no part of the claimed design.

1 Claim, 7 Drawing Sheets
